Primary Examiner — Robert M Spear*Assistant Examiner* — Darcey E Heflin(74) *Attorney, Agent, or Firm* — Woodard Emhardt Moriarty McNett & Henry LLP**CLAIM**

The ornamental design for a cap, as shown and described.

DESCRIPTION

FIG. 1 is a perspective view showing our ornamental design; FIG. 2 is a front elevational view of the ornamental design of FIG. 1; the rear elevational view being the same view thereof; FIG. 3 is a front elevational view, in full section, of the ornamental design of FIG. 1 as viewed along line 3-3 in FIG. 5;

FIG. 4 is a right side elevational view of the ornamental design of FIG. 1, the left side elevational view being the same view thereof;

FIG. 5 is a top plan view of the ornamental design of FIG. 1; and,

FIG. 6 is a bottom plan view of the ornamental design of FIG. 1.

In the drawings, the evenly-spaced broken lines depict environmental subject matter only that form no part of the claim; the dash-dot-dot-dash lines and broken lines immediately adjacent the shaded areas represent boundaries of the claim and form no part thereof.
